UNITED STATES PATENT OFFICE.

ESTELLE W. HATTENDORF, OF MEMPHIS, TENNESSEE.

UNDERGARMENT.

Application filed June 1, 1926. Serial No. 113,052.

The present invention relates to an undergarment, and the principal features of advantage reside in the combination of a closed crotch union suit, form fit in design, with a special fullness in the back, in the front, and at the hips, and with the bottom of the legs open but fastened tight just above the knees, by means of one or more fasteners.

This garment may be constructed with either bodice or built-up shoulders. As a result of the combination of these features, all of which are now known in the art, a number of new and desirable results are obtained. The looseness at the hips, etc., gives added comfort, whereas the tightness just above the knees, gives the wearer the sensation of having some clothes on. This effect is heightened by the use of a closed crotch, the fasteners providing for emergencies.

In connection with the fullness at the hips, this fullness in the leg provides full accessibility.

With the above and numerous other objects in view as will appear as the description proceeds, the invention resides in certain novel features of construction, and in the combination and arrangement of parts as will be hereinafter more fully described and claimed.

In the drawing:—

Figure 1 is a front elevation of the garment embodying the features of my invention,

Fig. 2 is a rear elevation thereof,

Fig. 3 is a fragmentary plan view showing the two rear segments, and

Fig. 4 is a plan view of one of the crotch segments.

Referring to the drawing in detail, it will be seen that this garment is made up of five segments, or pieces of cloth of suitable material sewed together. The front segment which is shown to advantage in Fig. 1, is designated generally by the letter A and includes an upper portion 5 and a pair of front leg portions 6. Slits 7 are provided at the waist line of the front segment A extending transversely for a short distance from the center thereof. The leg portions 6 are shaped at their outer side edges to provide a fullness at the hips as is indicated at H.

The inner edges of the leg portions 6 diverge outwardly and downwardly from each other. The back of the garment is made up of two rear segments, each of which is desig-

nated generally by the letter B and includes an upper portion 8 and a leg portion 9. These leg portions 9 are provided at their outer sides with curves to form the desired fullness at the hips as is indicated at H also. The outer side edges of segments B are secured as is indicated at 10 to the outer sides of the front segment A, except at the lower extremity of the leg portions 6 and 9, where an opening or slit 11 is provided in each leg and suitable fastening elements 12 associated therewith.

A portion of the inner edges of the leg portions 6 and 9 are sewed together as is indicated at 13 starting from the lower extremity of the garment and terminating a distance from the crotch thereof. Substantially triangular shaped segments C are shown sewed to the remaining portions of the inner leg portions 6 and 9, as is indicated at 14 and 15, and these segments C are partially sewed together along the line 16. Stitches close the slits 7.

Particular attention is now directed to Figs. 2 and 3. In Fig. 3, it will be seen that the inner edges of the segments B above the crotch are spaced relatively close together while the edges of the waist portions 8 are spaced rather far apart, so that in stitching these inner edges together, it is necessary to provide slits 18 so that portions of the segments B at the waist line must be tucked as is indicated at 19 so that the garment will fit snugly about the waist, the inner edges of said segments being sewed together as is indicated at 20 and 21 while the slits 18 are sewed together as is indicated at 22.

Shoulder straps 24 or other equivalent means may be provided at the top of the garment. When a garment has been constructed in accordance with the principles of this invention as explained in detail above, it will be quite apparent that the desirable looseness at the hips, etc., is provided to give added comfort as the garment is tight just above the knees and is closed at the crotch.

It is thought that the construction, operation, utility, and advantages of an undergarment embodying the features of this invention will now be clearly understood by those skilled in this art without a more detailed description thereof. The present embodiment of the invention has been disclosed in detail merely by way of example, since in actual practice it attains the features of advantage enumerated as desirable in the statement

of the invention and the above description. Numerous changes in the details of construction, in the combination and arrangement of parts may be resorted to without departing 5 from the spirit or scope of the invention as hereinafter claimed or sacrificing any of its advantages.

Having thus described my invention, what I claim as new is:—

- 10 An undergarment including a front segment comprising an upper portion and a pair of leg portions, the inner edges of which diverge downwardly and outwardly from each other at a point approximating the waist line of the garment, a pair of back segments each comprising an upper portion and a leg portion, said back segments having transverse slits extending outwardly from the inner edges thereof, the inner edges of 15 the back segments above the slits being spaced when the inner edges of the back seg-

ments below the slits are together before the segments are sewed together, the lowermost portions of said inner edges below the slits diverging downwardly and outwardly from each other, and a pair of substantially triangular shaped segments, the outer edges of the front and back segments being sewed together, portions of the inner edges of the leg portions of the segments being sewed together, 25 said triangular segments being sewed to the remaining inner diverging edges of the leg portions of the front segment, and the remaining portions of the diverging inner edges of the leg portions of the back segments and to each other, the inner edges of the back segments being sewed together and the slits being sewed closed so as to provide tucks therebelow.

In testimony whereof I affix my signature.

ESTELLE W. HATTENDORF.
